UNITED STATES PATENT OFFICE.

JOHN H. HAMMONTRE, OF LOS ANGELES, CALIFORNIA.

DERAILER.

1,423,495.

Specification of Letters Patent. Patented July 18, 1922.

Application filed January 3, 1921. Serial No. 434,623.

To all whom it may concern:

Be it known that I, JOHN H. HAMMONTRE, a citizen of the United States, residing at Los Angeles, in the county of Los Angeles 5 and State of California, have invented new and useful Improvements in Derailers, of which the following is a specification.

It is the object of this invention to provide a derailler for a car, particularly adapted to 10 be employed in a branch line leading from a main line of a railway system, so that it will be necessary for one of the train crew of a train about to move on to the main line from the branch line, to manually move the 15 derailler into inoperative position before the train can move on to the main line.

In devices of this character as heretofore constructed, the derailler removes an entire truck of a car from the tracks so that considerable time and energy is necessary to 20 replace the car truck upon the rails.

My invention provides means whereby the movement of a car is as efficiently stopped as by the deraillers now in use, but by means 25 of which only one wheel of a car is removed from the track so that it may be replaced upon the track through the expenditure of considerable less time and energy.

The invention will be readily understood 30 from the following description of the accompanying drawings, in which:

Figure 1 is a perspective view showing a portion of a branch line and having the improved derailler employed in connection with 35 one of the tracks.

Fig. 2 is a transverse section on the line 2-2 of Fig. 1.

In the drawings, I have shown usual rails 1 of a branch line mounted upon usual cross 40 ties 2 as by spikes 3.

Usual derailing mechanism is employed 45 including a casing 4 mounted upon an extension of one of the ties 2, and having an operating handle 5 and a signalling standard 6 projecting above the same. An operating lever 7 projects from the base of casing 4 and is actuated through manual operation of handle 5. This lever is connected to the usual operating rod 8 slideable in a bearing 9 50 suitably supported upon the ties.

The improved derailing mechanism includes a block 10 mounted between ties 2 beneath operating rod 8 and bearing plates 11 mounted upon the ties at the sides of 55 block 10 and extending laterally from one of the rails 1.

The section of this rail, which is above block 10 and the bearing plates 11 is separate from the rail 1. This rail section is shown at 12. It is laterally shiftable out of alignment with the rail proper by a connection provided between operating rod 8 and said rail connection, and when thus laterally shifted, it is adapted to slide on to bearing plates 11 as shown in dotted lines in Fig. 1. 60 65

The connection provided between rod 8 and the removable rail section includes a transverse arm 13 upon the end of the operating rod and having angularly disposed ends 14 received through the removable rail 70 section and connected thereto by means of nuts 15 threaded on to said angularly disposed ends.

By the construction as thus set forth it will be seen that actuation of handle 5 will 75 reciprocate operating rod 8, so as to move the removable rail section either into or out of alignment with the rail proper. When the rail section is in alignment with the rail, the car wheels will move over the same in 80 usual manner, but when the rail section is out of alignment, one of the car wheels will drop upon block 10 and thereby stop the car. The removable rail is formed with an inclined joint 20 between one end of the same 85 and the rail proper, so that when the removable section is out of alignment with the rail, one end of the latter forms an inclined end. The removable rail section is of sufficient 90 length to derail one car wheel only, and as a consequence, in order to replace the car wheel upon the track, it is only necessary to back the car so that the derailed wheel will run up the inclined end of the rail and back onto the track. The detachable rail section 95 is then moved back into alignment with the rail proper.

Various changes may be made without departing from the spirit of the invention as claimed. 100

What is claimed is:

1. A derailler for a track including actuating mechanism for the same and a section of a track rail removable by said actuating means to cause the wheel of a car upon said track to drop from the rail, the joint between said rail proper and removable section forming an inclined end for the rail proper. 105

2. A derailler for a track including actuating mechanism for the same and a section of a track rail removable by said actuating 110

means to cause the wheel of a car upon said track to drop from the rail, the joint between said rail proper and removable section forming means for allowing said wheel to be run back on to said rail.

3. A derailer for a track including a section of a track rail laterally shiftable, means for laterally supporting said section, means adapted to shift the same, said means comprising a laterally shiftable member and longitudinal members extending therefrom, the latter of said members having supporting engagement with said section.

4. In a derailer, a rail section normally positioned between the adjacent ends of track rails, said rail section being bodily movable laterally with respect to said track rails between which it is positioned, and the

joint between one end of said bodily movable rail section and the adjacent track rail 20 section being inclined.

5. In a derailer, a rail section normally positioned between the adjacent ends of track rails, said rail section being bodily movable laterally with respect to said track 25 rails between which it is positioned, the joint between one end of said bodily movable rail section and the adjacent track rail section being inclined, and a plate arranged beneath the ends of the track rail section and extending laterally therefrom to form a support for the bodily movable rail section when the same is shifted away from the track rails.

In testimony whereof I have signed my name to this specification.

JOHN H. HAMMONDRE.
